Inventor:

Albert G. Brewer.

ALBERT G. BREWER, OF HOPKINTON, MASSACHUSETTS.

Letters Patent No. 85,901, dated January 19, 1869.

ADJUSTABLE EXTENSION-PEDAL FOR PIANOS, &c.

The Schedule referred to in these Letters Patent and making part of the same.

To all whom it may concern:

Be it known that I, ALBERT G. BREWER, of Hopkinton, in the county of Middlesex, and State of Massachusetts, have invented a new and useful Improvement on "Adjustable Extension-Pedals" for Pianos and Melodeons; and I hereby declare that the following is a full, clear, and exact description of the construction and operation of the same, reference being had to the annexed drawings, making part of this specification.

The nature of my invention consists in having a rod of iron, or other metal, so bent at one end that it can, by means of a key, be attached to the pedal of a piano or melodeon, while the opposite end is raised to the right height for the foot, so that those who are unable to reach the pedal can, by this, work it with ease.

Figure 1 is a perspective view of the extension attached to the pedal.

Figure 2 is a sectional view of the foot-piece.

In fig. 1, A represents the pedal.

B is a rod, so bent at one end that it can, by means of the key E, be attached firmly to the pedal.

C is the foot-piece, and is made of wood.

D is a collar, slipping loosely on the rod B, and is secured to it by turning the foot-piece C, which has driven into it a bolt, F, shown in fig. 2.

The outer end has a thread upon it, and screws into the collar D. The object of this is to vary the height of the foot-piece C.

I claim as new, and desire to secure by Letters Patent—

1. The combined arrangement of the different angles in the rod B with the key E, substantially and for the purpose above described.

2. The arrangement of the foot-piece C, bolt F, and collar D, substantially as and for the purpose above described.

ALBERT G. BREWER.
